COMBINATION LETTER, BILL, RECEIPT,
AND ENVELOPE

Walter J. Mattson, Brooklyn, N. Y.

Application January 12, 1940, Serial No. 313,576

1 Claim. (Cl. 229—92.1)

This invention relates to a combination letter, bill, receipt and envelope.

An object of this invention is to provide a combination letter, bill, receipt and envelope made from a single sheet of paper, which may be sent through the mails, and is provided with a window through which the name and address of the addressee may be seen.

A further object of this invention is to provide an article of the character described which may be readily opened by the addressee by tearing away the scored border edge portions leaving a folded sheet which may be opened up exposing a letter addressed to the addressee together with a bill and receipt, means being provided to permit the letter, bill and receipt to be separated for separate filing and to permit return of the receipt.

Still another object of this invention is to provide a neat and simple combination letter, bill, receipt and envelope of the character described which shall be relatively inexpensive to manufacture, easy to use and practical and efficient to a high degree.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claim.

In the accompanying drawing, in which is shown one of the various possible illustrative embodiments of this invention:

Fig. 1 is a top plan view of the combination letter, bill and receipt embodying the invention before sealing;

Fig. 2 is a top plan view of the sealed article and showing an edged portion torn away, in dotted lines;

Fig. 3 is a cross-sectional view taken on line 3—3 of Fig. 2; and

Fig. 4 is a cross-sectional view taken on line 4—4 of Fig. 2.

Referring now in detail to the drawing, 10 designates a combination letter, bill, receipt and envelope embodying the invention. The same is made from a single sheet 11 of paper or the like material. The sheet 11 is preferably rectangular in shape. The upper and lower edges 12 may be longer than the end edges 13. Inwardly of the edges 12 are parallel lines of scoring 14, and inwardly of the end edges 13 are parallel lines of scoring 15. Between the lines 55

of scoring 14 and 15 and the edges 12 and 13 of sheet 11 is a rectangular border portion. The lower half 16 of the border portion is provided with adhesive and the upper half 17 of the border portion does not have adhesive, but when the sheet 11 is folded about its longitudinal mid-section the border portion 17 may be sealed to the border portion 16 by moistening the latter. The parallel lines of scoring 16 are inter-connected by a scored line 20 parallel to and disposed midway between the scored lines 14. Sheet 11 may be folded about said scored line 16.

The scored line 20 is connected to the lower scored line 14 by a scored line 21 parallel to the scored lines 15 and closer to the right edge of the sheet 11 than to the left edge and dividing the lower half of the sheet into sections 22 and 23. On section 22 there may be printed a bill and on section 23 there may be printed a receipt.

The upper half of the sheet 11 is divided by a printed line 25 somewhat closer and parallel to the left scored line 15 than to the right, into two sections 26 and 27. On section 27 there may be printed a letter head leaving space for typing or writing a letter. Section 26 is formed with a horizontal cut-out or window opening 28 parallel to the scored line 20. Covering the window opening is a sheet 30 of transparent material pasted to the upper surface of sheet 11. On section 22 is a printed outline 31 similar to the window 28. The window opening 28 and the outline 31 are symmetrically arranged with respect to the scored line 20.

It will now be understood that after the items have been typed on the bill, and the letter written and the receipt filled in where necessary, the sheet 11 may be folded about the scored line 20 and the border portions 17 sealed to the border portions 16. The sealing produces an envelope which may be mailed. The name and address of the addressee typed within the outline 31 may be seen through the window opening 28.

When the letter is received the border edges may be torn away along the scored lines 14 and 15, the recipient of the letter may then read the letter in section 27, and will also have the bill of section 22 and receipt of section 23. The receipt and the bill may be torn away from the letter by reason of the scored lines 20 and 21.

It will now be understood that the article 10 is a combination letter, bill and receipt and may furthermore be mailed without any additional envelopes. Further, the bill and receipt may be separated from the letter by the addressee. Furthermore the address does not have to be typed

on the outside of the article as the name on the bill can be seen through the window opening 28. The device can be easily sealed and also easily opened.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:

An article of the character described compris-

ing a rectangular sheet, said sheet being formed with scored lines parallel to and disposed inwardly from the lower, upper and end edges thereof and said sheet being further formed with a scored line parallel to the upper and lower edges thereof and disposed midway between said edges and inter-connecting the scored lines at the end edges of said sheet, the scored line parallel to the upper and lower edges being inter-connected to the scored line at the lower edge of the sheet by a scored line parallel to the end edges of the sheet, the lower half of the border portions below the scored line which is parallel to the upper and lower edges being provided with adhesive, said sheet being formed with a window opening adjacent one corner thereof, and a transparent sheet covering said opening.

WALTER J. MATTSON.
